UNITED STATES PATENT OFFICE.

HANS CHRISTENSEN, OF CHICAGO, ILLINOIS.

EARTH-PULVERIZING MACHINE.

1,391,614.

Specification of Letters Patent. Patented Sept. 20, 1921.

Application filed November 16, 1920. Serial No. 424,529.

To all whom it may concern:

Be it known that I, HANS CHRISTENSEN, a subject of the King of Denmark, residing at Chicago, in the county of Cook and State 5 of Illinois, have invented certain new and useful Improvements in an Earth-Pulverizing Machine; and I do hereby declare the following to be a full, clear, and exact description of the invention, such as will 10 enable others skilled in the art to which it appertains to make and use the same.

This invention relates to an earth pulverizing machine, and the object is to provide in connection with a series, or a plurality 15 of series, of rotatable disks,—rotary devices associated with each series of disks and geared thereto, each of the devices last named including an axial element and arms radiating therefrom.

20 A further object is to provide, in connection with the construction above specified, means for varying the angle between the axial elements mounting the rotary disks.

A still further object is to provide, in a 25 device of the type indicated, a main frame including a plurality of pairs of shaft mounting devices, with the shafts mounted therein, a series of disks carried by each shaft, and particular means for varying the 30 angular relation of the shafts.

A still further object is to provide, in the 35 above construction, a plurality of bars, connected respectively to the sections of the device mounting the series of disks, and connected with links operated directly by a worm wheel, the latter being controlled by a worm shaft constituting a part of the controlling mechanism operated by the driver 40 of the machine.

45 With the foregoing and other objects in view, the invention consists in the novel construction, combination, and arrangement of elements hereinafter described and claimed, it being understood that modifications or variations in details of construction may be made, within the scope of the appended claims.

In the drawings:

50 Figure 1 is a top plan view, one of the guard plates being removed, and the pivoted frames being at an angle with reference to each other.

55 Fig. 2 is a vertical section on the line 2—2 of Fig. 1, showing the controlling means for one of the pivoted frames, in ele-

vation, and showing the drive for the earth working elements of one pivoted frame.

Fig. 3 shows one of the pivoted frames in an elevated position, a portion of the main 60 frame also being shown.

Fig. 4 is a view chiefly in top plan, showing the operating and controlling elements for the pivoted frame, detached from the supporting structure.

65 Figs. 5, 6 and 7 show details of construction of the machine, and especially of the pivoted frame, the operative elements carried thereby and the mounting of the individual earth working devices on their axes.

70 The main frame includes a transverse element 10 mounting a seat 11 for the driver, and also mounting the controlling devices referred to below, this transverse element having connected with its opposite ends 75 diagonal braces 13 and 14, the forward ends of which are off set as shown at 15 and have connection with the parallel bars 16 and 17. Between the forward ends of the latter—that is the bars 16 and 17—is a block or 80 draft element 18, and the rear ends of the bars are offset and connected by means of bolts 19 with a downwardly turned flange of bar 10.

85 Extending rearwardly from each end of the bar 10 is a bracket 21 or 22 as the case may be, this bracket having connection with an element 23, on each side of the machine, adapted to receive the central portion of one of the shafts mounting the disks 24. 90 The shafts are designated 25, and may be thrown to a position in approximate alignment, and may be also thrown out of alignment, so that they will assume various angular positions with reference to each other. 95

The shafts 25 may be square in cross section, corresponding openings being provided in the central portions of the disks, so that the latter are non-rotatable on the shafts, but are rotatable with the shaft, each shaft 100 carrying a sprocket wheel 27 on its inner end, and a sprocket wheel 28 on its outer end, these wheels and the smaller wheels 29 and 30 on shafts 31 being rotatable together, in view of the drive through the chains 32. 105 These shafts 31 may also be square in cross section if desired, and they carry a plurality of series of teeth, flattened as shown at 33, toward the end portions which are thereby sharpened, and which act in conjunction 110 with the disks, with which they alternate,

for producing the pulverizing operation. Arms projecting from opposite sides of the shafts 31 are in alinement, in the construction shown, and they alternate with arms or teeth extending perpendicularly with reference to those first referred to. The teeth project to a point between the outer edges of the disks and the central portions thereof, in order to insure effective coöperation. The 10 disks are spaced by tubular spacing elements 35.

In order to make suitable provision for the mounting of the shafts, and for the control of the two main sections of the apparatus, I provide a frame for each section, the frame including an upper transverse element 36, an outer frame element 37 connected therewith, and an inner frame element 38, the devices 37 and 38 each being 15 provided with bearings for the mounting of shafts 25 and 31. A guard plate, formed as shown, is provided for each section of the machine and is connected with each upper transverse element 36. Chains 40 and 41 20 are connected respectively with the guard members, and are adapted to engage the hooks or pins 42 on element 10, this arrangement permitting of the raising of the rear portion of each frame, and therefore of the 25 elevation of the shaft 31 to a given extent with reference to shaft 25.

Pivottally connected with each frame is a bar 44 having an offset portion 45 and extending forwardly to a point where it has 30 pivotal connection with a link 46, extending in a vertical direction and movable angularly with reference to a transverse pin 48 passing through bracket members 49. A worm wheel 50 is mounted on this pin, and the links or arms just referred to are rigid with reference to the worm wheel, so that the links are shifted upon the rotation of 35 that wheel through any given angle.

A worm 51 coöperates with the worm 45 wheel and is mounted on a vertical shaft 52 carrying a wheel 53, within convenient reach of the driver. A bracket 54 may be formed as shown and includes a central portion 50 apertured for the accommodation of the vertical shaft mounting the worm. The respective sections of the machine are movable about the pivotal point upon the rotation of the worm and worm wheel, in view of the movement imparted to the bars connected 55 with the respective frames, and the angular relation of the shafts carrying the disks may therefore be varied, and the shafts 31 remaining parallel with the shafts 25, will be similarly controlled.

In order to permit of the swinging of the 60 pivoted section or frames about a horizontal axis, I connect each frame with one of the bars 44 by employing a bracket 56 mounted on the inner end of the pivoted frame, the bar being pivoted to the bracket. The outer

end member of the pivoted frame is movable about the shaft 25 when this frame, or the rear portion thereof, is elevated.

Having thus described the invention, what I claim is:—

1. In a machine of the class described, a main frame, frames pivotally connected with each end of the main frame, a plurality of shafts mounted in each pivoted frame, means for imparting movement from one shaft to the adjacent shaft in the same frame, earth working devices mounted on said shafts, and means for changing the relative position of the pivoted frames. 70

2. In a machine of the class described, a main frame, frames pivotally connected therewith, earth working devices mounted in the pivoted frames and including rotary axial elements, a bar connected with each pivoted frame to one side of its pivotally connection with the main frame and acting to move the latter about its pivotal point, and means for controlling the bar simultaneously, for angularly adjusting the pivoted frames. 80

3. In a machine of the class described, a main frame, frames pivotally connected therewith, earth working devices mounted in the pivoted frames and including rotary axial elements, a bar connected with each pivoted frame to one side of its pivotally connection with the main frame and acting to move the latter about its pivotal point, and worm gearing for controlling the bars simultaneously, for angularly adjusting the 95 pivoted frames and holding them in the adjusted position. 90

4. In a machine of the class described, a main frame, frames pivotally connected therewith, earth working devices mounted in each pivoted frame and including a series of disks and a rotary toothed element 105 coöperating with the series of disks and means for changing the relative position of the disks of one frame with reference to 110 those of the other of said frames. 105

5. In a machine of the class described, a main frame, frames pivotally connected therewith, earth working devices mounted in each pivoted frame and including a series of disks and a rotary toothed element coöperating with the series of disks, and means for changing the relative position of the disks of one frame with reference to 115 those of the other of said frames, the means last named comprising a plurality of bars and devices for shifting the bars simultaneously. 120

6. In a machine of the class described, a main frame, frames pivotally connected therewith, each of the pivoted frames including a transverse element, and end sections connected therewith, a plurality of shafts having their bearings in said end sections, means for imparting movement 130

from one shaft to the other of said shafts, a series of disks rotatable with one of the shafts, and a series of radial arms carried by the other shaft, the disks being spaced 5 apart, and the arms passing between the spaced disks during the rotation of the aforesaid shafts.

7. In a machine of the class described, a frame including a transverse element, end 10 sections connected therewith and providing bearings, parallel shafts mounted in the bearings, a series of disks mounted on one of the shafts and non-rotatable thereon, tubular spacing elements surrounding the 15 shafts last named between the disks, and a series of radial arms carried by the adjacent shafts, the arms being movable between the disks, and coöperating therewith, and means for imparting movement from 20 one of said shafts to the other.

8. In a machine of the class described, a main frame, a pivoted frame coupled to the main frame and having independent adjustment about a vertical and a horizontal axis, 25 and independent means for effecting either adjustment irrespective of the position of the frame.

9. In a machine of the class described, a

main frame, pivoted frames coupled to the main frame and having independent adjustment about vertical and horizontal axes, 30 means for simultaneously adjusting the pivoted frames about their vertical axes, and means for independently adjusting the pivoted frames about their horizontal axes. 35

10. In a device of the class described, a main frame, pivoted frames connected therewith, earth working devices each including an axial element mounted in the pivoted frame, each of the frames last named being 40 movable about a vertical axis, bars connected with the frames for effecting such movement, arms pivotally connected with the bars, a wheel rigid with reference to the arms and controlling the movement thereof, 45 and of the bars, said means being rotatable on a horizontal axis, and means rotatable on a vertical axis for controlling the element imparting movement to the arms.

In testimony whereof I affix my signature 50
in presence of two witnesses.

HANS CHRISTENSEN.
